UNITED STATES PATENT OFFICE

JOHN A. JESSEN, OF WHITINSVILLE, MASSACHUSETTS, ASSIGNOR TO WHITIN MACHINE WORKS, OF WHITINSVILLE, MASSACHUSETTS, A CORPORATION OF MASSACHUSETTS

GUIDING DEVICE FOR LONG DRAFT APRONS

Application filed June 16, 1930. Serial No. 461,277.

This invention relates to the so-called "long draft" system of cotton spinning in which the cotton roving is supported between movable belts or aprons as it is advanced from the 5 intermediate drawing rolls to the front drawing rolls in a spinning machine.

The sides of the supporting frames for the aprons are commonly recessed to slip over the lower intermediate drawing roll, around 10 which the lower apron travels. This frame not only supports the aprons but also acts to guide the edges of the aprons.

The frame is not entirely effective and satisfactory for this latter purpose, however, as 15 the apron is free from the frame for a substantial portion of the periphery of the roll and has a marked tendency to crowd off to one side and to curl over the edge of the fluted portion of the roll as it passes the recess in the 20 frame.

It is the object of my present invention to provide a device for supplementing the guiding action of the supporting frame and for preventing the apron from being displaced 25 laterally as it passes the recess in the frame.

A further object is to provide a device for such purposes which is simple and inexpensive to construct and which is very easily applied to its intended uses.

30 My invention further relates to arrangements and combinations of parts which will be hereinafter described and more particularly pointed out in the appended claim.

A preferred form of the invention is shown 35 in the drawing, in which

Fig. 1 is a sectional end elevation of a set of drawing rolls with my improvements applied thereto;

Fig. 2 is a partial plan view, looking in the 40 direction of the arrow 2 in Fig. 1;

Fig. 3 is a side elevation of the supporting frame;

Fig. 4 is an end view of the guiding device;

Fig. 5 is a side elevation thereof, looking in 45 the direction of the arrow 5 in Fig. 4; and

Fig. 6 is a plan view of a blank from which the guiding device may be formed.

Referring to Fig. 1, I have indicated back drawing rolls 10 and 11, intermediate drawing 50 rolls 12 and 13 and front drawing rolls

14 and 15. The roving R is fed to the back drawing rolls 10 and 11 and the yarn Y is delivered from the front drawing rolls to the spinning mechanism.

A supporting frame is mounted on the intermediate drawing rolls 12 and 13 and comprises side members 20 and cross bars or connecting members 21 and 22. The side frame members 20 are provided with lower and upper recesses 23 and 24. The lower recesses 23 fit over the unfluted portions of the lower intermediate drawing roll 12 and the recesses 24 receive the corresponding portions of the upper intermediate drawing roll 13. 55

Aprons 30 and 31 are mounted on the intermediate rolls 12 and 13 and are guided around cross rods 32 and 33 held against edge portions 34 of the side frame members 20 by the belts 30 and 31. The cross bars 32 and 33 are vertically positioned and spaced apart 60 70 by V-shaped lugs or projections 35 on the edge portions 34.

The cross bars 32 and 33 may be formed as a single U-shaped member having the two guide portions connected at one end, as indicated at 37 (Fig. 2) and having the opposite ends turned over, as indicated at 38, to prevent lateral displacement. 75

With this construction, the aprons 30 and 31 are firmly supported in operative position, 80 with parallel runs closely adjacent, and they are also restrained from lateral or axial displacement by the side frame members 20.

It will be noted, however, that the recesses 23 leave the lower belt 30 unsupported for 85 nearly half of the periphery of the drawing roll 12. While passing these recesses, it has been found that the lower apron has a marked tendency to run sidewise and to curl down over the edge of the fluted portion of the 90 drawing roll. In this way, the edge portions of the apron soon become worn and irregular and it is necessary to replace the aprons before the other portions thereof show wear. 95

To prevent this axial displacement, I have provided the guiding device shown in detail in Figs. 4, 5 and 6. The device is preferably formed from a single piece of sheet metal having the general form shown in Fig. 6 and 100

comprising a middle or connecting portion 40 and end guiding portions 41. The edges 42 and 43 of the portion 40 are bent downward, as indicated in Fig. 4, and the end portions 41 are bent perpendicular to the connecting portion 40.

It will be noted that the end portions 41 are segmental in shape so that when placed in the operative position indicated in Fig. 1, 10 these end portions 41 cooperate with the side plates 20 to form guiding surfaces entirely around the lower drawing roll 12.

The guiding device is readily placed in position by hooking the ends 41 under the 15 drawing roll 12 and seating the connecting portion 40 on the cross bar 21 of the supporting frame. With this guiding device in place, axial displacement of the apron 30 20 is eliminated and the useful life of the apron is much prolonged.

Having thus described my invention and the advantages thereof, I do not wish to be limited to the details herein described, otherwise than as set forth in the claim, but what 25 I claim is:—

In a spinning frame having upper and lower drawing rolls, upper and lower long draft aprons, and a separate supporting frame for each pair of said aprons with spaced side 30 plates and with upper and lower cross bars connecting said side plates substantially at opposite sides of said lower drawing roll, in combination, an apron guiding device mounted in said supporting frame between the side 35 plates thereof and between said cross bars and bridging the gap between adjacent portions of said side plates, said guiding devices having portions between and abutting said upper and lower cross bars and also partially 40 embracing said lower cross bar, and said guiding device being securely held from displacement thereby but being detachable and readily removable manually from guiding position.

45 In testimony whereof I have hereunto affixed my signature.

JOHN A. JESSEN.
